United States Patent Office

Des. 200,862
Patented Apr. 13, 1965

200,862

TOY PARAGLIDER OR SIMILAR ARTICLE

William L. Effinger, Jr., Branford, and Henry Struck,
Hamburg, Conn., assignors to The A. C. Gilbert Com-
pany, New Haven, Conn., a corporation of Maryland

Filed Dec. 4, 1963, Ser. No. 77,662

Term of patent 14 years

(Cl. D34—15)

Fig. 1

Fig. 2

Fig. 4

Fig. 3

FIG. 1 is a side elevational view of a toy paraglider showing our new design;

FIG. 2 is a top plan view thereof;

FIG. 3 is a bottom plan view thereof; and

FIG. 4 is a front elevational view thereof.

We claim:

The ornamental design for a toy paraglider or similar article, substantially as shown.
